OUTBOARD PROPELLER MECHANISM FOR
BOATS WITH ECCENTRICALLY MOUNTED
SHAFT HOUSINGSArthur W. Wanzer, Quincy, Mass., assignor to
Murray & Tregurtha, Inc., Quincy, Mass., a
corporation of Massachusetts

Application May 28, 1948, Serial No. 29,710

2 Claims. (Cl. 115—35)

1 This invention relates to propeller mechanism for boats of the type in which the propeller is carried on a horizontal propeller shaft situated at the lower end of a vertically extending propeller-supporting housing and is driven by a driving shaft extending vertically through the housing, and in which said housing is mounted to turn about a vertical axis for steering the boat.

In propeller mechanism of this type the transmission of power through the vertical driving shaft produces a turning moment on the vertically extending housing tending to turn it about its vertical axis in the same direction as that in which the driving shaft is rotating, and if this turning moment is unbalanced it places an extra load on the steering mechanism when the latter is actuated to turn the housing in a direction opposite to such turning moment and assists the steering operation when the housing is turned in the opposite direction, thus making it much harder to steer the boat in one direction than in the other.

In order to overcome this difficulty it has been proposed to offset the propeller shaft laterally from the vertical shaft of the housing so that when the propeller is operating, the thrust on the propeller shaft subjects the housing to another turning moment that is in a direction opposite to that in which the housing is subjected by the rotation of the vertical driving shaft. A propeller mechanism having this construction is illustrated in the Mathewson Patent No. 2,335,597, November 30, 1943.

The turning moment to which the housing is subjected when power is being transmitted through the driving shaft may for convenience be referred to as the "primary turning moment," and the opposing turning moment to which the housing is subjected by the offset relation between the axis of the propeller and the vertical axis about which the housing turns may be referred to as the "secondary turning moment."

In propeller mechanism of this type, the primary turning moment on the housing varies with the power being transmitted through the driving shaft, and the secondary turning moment depends upon the offset relation between the propeller shaft and the vertical shaft of the propeller-supporting housing.

It is one of the objects of my present invention to provide a novel construction by which the amount that the propeller shaft is offset laterally from the vertical axis of the propeller-supporting housing may be varied as necessary to

bring the primary and secondary turning moments substantially into a balanced relation.

In the drawings in which I have illustrated a selected embodiment of the invention,

5 Fig. 1 is a fragmentary view of a boat having my improved propeller mechanism mounted thereon;

Fig. 2 is an enlarged sectional view on the line 2—2, Fig. 1;

10 Fig. 3 is a vertical sectional view through the propeller-supporting housing.

Figs. 4, 5 and 6 are sectional views on the line 4—4, Fig. 3 illustrating different adjustments that may be made in the propeller-supporting housing to secure different offset relations between the propeller shaft and the axis of said housing and therefore different degrees of the secondary turning moment.

In Fig. 1 of the drawing 1 indicates a boat, barge, or other vessel which is equipped with my improved propeller mechanism, the latter comprising a power generator 2, such for instance as an internal combustion engine, having a power shaft 3, a propeller 4, and suitable driving connections between the power shaft 3 and the propeller 4.

The propeller 4 is shown as carried by a propeller shaft 5 that is mounted in the lower end of a propeller-supporting housing 6 that houses a vertical drive shaft 7 by which the propeller shaft 5 is connected to the power shaft 3.

The propeller-supporting housing 6 is mounted for turning movement about a vertical axis for steering the boat, this being a common expedient in outboard propeller mechanisms of this type.

35 Said propeller-supporting housing 6 is shown as supported by a main housing or frame member 8 that is secured to the base element 16 on which the power generator 2 is mounted, the latter being suitably secured to the deck of the vessel 1.

As stated above, the propeller-supporting housing 6 is mounted for turning movement about a vertical axis for steering the boat, and for this purpose the upper end portion 10 of said housing is carried in suitable bearings 11 with which the portion 8 of the frame is provided. Suitable steering means is provided similar to that shown in my U. S. Patent No. 2,458,813 of January 11, 1949 for turning the housing in order to steer the vessel. The upper end 10 of the housing 6 has rigid therewith a worm gear 17 which meshes with a worm 15 on a transverse shaft 14, the latter is connected by a chain and sprocket 13 and bevel gears 40 to a longitudinally extending shaft 9 carried by the base 16. Said shaft 9, in

45 55

turn, is connected by a chain and sprocket 12 with the shaft 18 of the steering wheel 19 so that by turning the steering wheel, the housing 6 may be turned about its vertical axis.

The vertically extending drive shaft 7 is made with an upper section 20 that is connected to the power shaft 3 by means of suitable gearing, a lower section 21 that is connected to the propeller shaft 5 by bevel gears 23, and an intermediate section 24 which is connected to the upper and lower sections by universal joints 25.

The upper shaft section 20 is connected by bevel gears 22 to a horizontal shaft 43, which in turn is connected to the power shaft 3 by means of bevel gears 44. Said upper shaft section 20 is co-axial with the upper portion 10 of the housing and therefore has the same axis as that about which the housing turns.

The lower shaft section 21 is mounted in bearings 26 carried by the housing 6. The axes of the shaft sections 20 and 21 are parallel to each other but offset laterally from each other as clearly seen in Fig. 3. The axis of the lower shaft section 21 is in the same vertical plane as the axis of the propeller shaft 5. In other words the axes of said shaft section 21 and propeller shaft 5 intersect each other.

The propeller-supporting housing 6 is constructed so that this offset relation between the shaft section 20 and the axis of the propeller shaft may be varied, thereby to vary the offset relation between the propeller shaft and the vertical axis about which the housing 6 turns, and by this means the degree of the secondary turning moment on the housing may be varied.

This end is accomplished by making the housing 6 in two sections, an upper section 10 which is mounted in the bearings 11 and which is co-axial with the upper shaft section 20, and a lower section 27 which carries the lower shaft section 21 and the propeller shaft 5. The lower end of the upper housing section 10 is provided with a circular recess 29, the center of which is offset laterally from the axis of the upper housing section 10 as clearly seen in Fig. 3, said recess receiving the upper end 28 of the lower housing section 27. The two housing sections are secured together by means of bolts 31 which extend through a flange 30 with which the lower housing section 27 is provided and which are screw threaded into a rib 32 on the lower end of the upper housing section 10.

There are a plurality of these attaching bolts 31 equally spaced about the flange 30 as shown in Figs. 4, 5 and 6, and by this means the two housing sections can be attached together in any one of a plurality of different angular positions about the center of the circular recess 29, or, what is the same thing, about the axis of both the lower housing section 27 and the lower shaft section 21. When the two housing sections have the relative position shown in Figs. 3 and 4, the offset relation between the lower shaft section 21 and the upper shaft section 20 in a direction at right angles to the propeller shaft is at its maximum as indicated by the lines 33 and 34, the line 33 indicating the axis of the lower shaft section 21, and the line 34 indicating an extension of the axis of the upper shaft section 20 and also representing the axis about which the housing 6 turns.

If the two housing sections 10 and 27 are separated and then turned relative to each other about their axes and are again coupled together in relative positions in which the axis of the propeller shaft 5 intersects the axis of the housing 75

section 10 and the upper shaft section 20, which is the condition illustrated in Fig. 5, the offset relation between the propeller shaft 5 and the vertical axis of the housing 6 in a direction at right angles to the propeller shaft will be reduced to zero. In other words the direction of the forward thrust of the propeller on the propeller shaft will be in a line intersecting the vertical axis of the housing 6.

- 10 If the two housing sections 10 and 27 are separated and then coupled together again in an intermediate position such as shown in Fig. 6, the offset relation between the propeller shaft 5 and the vertical axis of the housing 6 in a direction at right angles to the propeller shaft 5 will be somewhere between the maximum offset relation shown in Figs. 3 and 4 and the zero relation shown in Fig. 5, such relation being indicated by the lines 33 and 34 in Fig. 6.
- 15 By this means it is possible to connect the upper and lower housing sections 10 and 27 of the propeller-supporting housing 6 so as to produce any desired offset relation between the maximum illustrated in Figs. 3 and 4 and the minimum or zero relation shown in Fig. 5.

I claim:

1. Propeller mechanism for boats comprising a vertically extending propeller-supporting member, a propeller carried by said member, means for operating the propeller including a driving shaft extending longitudinally of the propeller supporting member and a horizontal propeller shaft on which the propeller is mounted, said propeller supporting member having an upper section and a lower section separable from said upper section, said driving shaft presenting an upper shaft section journaled in the upper section of the propeller supporting member, a lower shaft section journaled in the lower section of said propeller supporting member, and an intermediate section connecting said upper and lower shaft sections, the axes of the upper and lower shaft sections being parallel but having a permanent fixed offset relation in a lateral direction and the axis of the lower shaft section intersecting that of the propeller shaft, means for turning the propeller supporting member bodily about the axis of the upper shaft section to steer the boat, and means detachably connecting the upper and lower sections of the propeller supporting member with the propeller shaft in any one of various radial positions relative to the axis of the lower shaft section, thereby to vary the amount which the propeller shaft is offset from said vertical axis.
- 30 2. Propeller mechanism for boats comprising a vertically extending propeller supporting housing, a propeller carried by said housing, means for rotating the propeller including a vertically extending driving shaft enclosed in said housing and a horizontal shaft on which the propeller is mounted, said housing presenting an upper housing section and a lower housing section, means supporting said upper housing section for turning movement about a vertical axis for steering the boat, said upper housing section having in its lower end a downwardly facing circular recess, the center of which is offset laterally from said vertical axis, said lower housing section having at its upper end a circular portion fitting said circular recess, said driving shaft presenting an upper shaft section journaled in the upper housing section coaxial therewith, a lower shaft section journaled in the lower housing section and coaxial with said circular recess and there-

fore offset laterally from the vertical axis, and an intermediate shaft section connecting the upper and lower shaft sections, means mounting the horizontal propeller shaft in the lower housing section with its axis intersecting that of the lower shaft section, and means for detachably securing said housing sections together with the propeller shaft occupying any one of a plurality of positions radial to the axis of the lower shaft section.
